UNITED STATES PATENT OFFICE.

JOSEPH M. TOWNE, OF EAST ORANGE, NEW JERSEY.

TEMPORARY BINDER.

1,144,447.

Specification of Letters Patent. Patented June 29, 1915.

Application filed August 7, 1914. Serial No. 855,625.

To all whom it may concern:

Be it known that I, JOSEPH M. TOWNE, a citizen of the United States, residing at East Orange, Essex county, State of New Jersey, have invented certain new and useful Improvements in Temporary Binders; and I do declare the following to be a full, clear, and exact description of the invention, such as will enable others skilled in the art to which it appertains to make and use the same.

This invention relates to certain new and useful improvements in binders for magazines, periodicals, pamphlets, or telephone 15 directories, and books of the same general character, and the primary object of the invention is to provide a binder in which a plurality of binder members are employed, which members are connected so as to be 20 capable of expansion and contraction to thus be easily and quickly applied to and removed from the back structure and from the magazines or pamphlets which are to be secured to the back.

25 A further object of the invention is to provide a binder which can be adapted to thick or thin magazines and pamphlets and the like.

In the drawings: Figure 1 is a view, 30 partly in side elevation and partly in section of the present invention; Fig. 2 is a top plan view; Fig. 3 is a section on the line 3—3 of Fig. 1; Fig. 4 is a view similar to Fig. 1 of a slightly modified form of the 35 invention; Fig. 5 is a section on the line 5—5 of Fig. 4; Fig. 6 is a view similar to Fig. 1 of a further modified form of the invention; Fig. 7 is a detail perspective view of one of the slotted end posts; Fig. 8 is a 40 side elevation of a modified form of the pivoted binding members; Fig. 9 is a view similar to Fig. 8 of a further modified form of pivoted binding members; Figs. 10 and 11 are side elevations of still further modified 45 forms of the invention; Fig. 12 is a top plan view of another modified form of the invention; Fig. 13 is a section on the line 13—13 of Fig. 12; Fig. 14 is a section on the line 14—14 of Fig. 12; and Fig. 15 is a 50 perspective view of still another modified form of the invention.

The primary or essential feature of the present invention, resides in a plurality of members engageable with the magazine or 55 the like, and pivotally or otherwise connected, so as to be capable of expansive and

contractile movement so as to be engaged with and disengaged from a plurality of stationary points on a back structure.

In the present embodiment of the invention, a pair of metal members 1 of strip-like form are employed to illustrate one manner in which the invention can be carried into practice, the members 1 being pivotally connected at 2 and locked against 60 pivotal movement by a pin or stud 3 carried by one of the members and engageable in and disengageable from an aperture 4 formed in the other member, by flexure of the members, the members being formed of 65 thin metal so as to allow the flexing thereof for the purpose indicated.

The back structure generally designated 5, may be of any preferred or desired structure, and is provided with spaced end posts 75 or keepers 6 which in the form shown in Figs. 1 and 2 are made of sheet metal, bent to form bases or feet 7 which are rigidly secured by suitable fastening means to the back 5, and abutments or right angular end 80 walls 8, which latter are slotted at 9.

As depicted in Fig. 3 of the drawings, the slots are located at varying distances from the back 5 for the purpose of accommodating magazines that may be bound very 85 close to or at a distance from the edge of the back. In this form of the invention, the ends of the members 1 are alined with the slots 9 when the members are in the contracted dotted line position shown in Fig. 1, 90 after which the members are expanded, the act of expansion causing the ends of the members to pass through the slots 9 into the full line position shown in said Fig. 1. It will of course be understood that the members 1 are first engaged between the leaves of the magazine, at the center of the latter and adjacent to the bound edge thereof, the binding of the magazine being indicated as 95 stapling S in Fig. 1.

In Figs. 4 and 5 of the drawings, a modified structure of keeper 6^a is shown in which no slots whatever are employed. In this form of the invention, the keepers are provided with overhanging ledges 10 which engage and prevent outward movement of the ends of the members 1^a by virtue of the latter engaging beneath or under the ledges. The members 1^a, can thus be shifted freely and at will from end to end of the keepers, 105 end flanges 11 being formed on the ledges to engage the ends of the members 1^a so as to 110

prevent the latter from being completely and laterally moved out of the keepers.

In cases where it is desired to have the keepers of slight depth or thickness and 5 large or thick books are to be bound, then the form of the invention shown in Fig. 6, is employed, in which the keepers 6^b have a series of slits 12 which receive fingers 13, carried by right angular shanks 14 that are 10 formed on the members 1^b. With this form of keeper, it is also possible to use members 1^x and 1^y which have fingers directly borne by their ends as indicated at 13' in Fig. 8 and 13'' in Fig. 9.

15 By referring to Figs. 10 and 11 it will be seen that by providing members 1^e of relatively considerable width, same may, in the position shown in Fig. 10 have their fingers 13^a engaged in the slots of keepers 6^e to hold large books, or by reversing the 20 fingers 13^a on members 1^e as shown in Fig. 11, the wider fingers 13^a may be placed in the slots to hold relatively thin books.

In Figs. 12, 13 and 14, the keepers are in 25 the form of cross-rods 14 which are provided with a series of annular spaced grooves 15 adapted to receive the U-shaped jaws 16 formed directly at and on the ends of the members 1^d. This form of the invention 30 is also applicable to use as a follower in bill files and the like as indicated at 17, in Fig. 15, in which the rods 14 act as posts which extend at right angles to the base board of the bill file and which pass through 35 perforations formed in the bills for their reception.

It will be understood that the number of 40 the slots or grooves which receive the ends of the binding members may be increased as desired, without departing from the spirit and scope of the invention.

From the above it will be apparent that the principle of the invention remains the same in each form of the invention disclosed, namely, the expansible and contractile binding elements are engageable between and disengageable from between two relatively stationary points, posts, or abutments, which elements when expanded engage the abutments or posts and retain the magazine or the like, or bills in stationary 45 relation thereto.

What is claimed is:—

1. In combination with a pair of spaced 55 stationary keepers, a pair of overlapping

pivotaly connected thin metal strips formed to engage the keepers at their outer ends and being engageable with and disengageable from the keepers by expansion and contraction of the strips, a stud on one strip and the other strip having an aperture to receive the stud so as to hold the strips locked against expansion and contraction. 60

2. In a loose leaf binder, in combination with a pair of keepers, a pair of pivotally connected flexible strips having means to engage the keepers, and means to lock said strips against pivotal movement, said means being engageable and disengageable by flexure of said strips. 65

3. In a loose leaf binder, in combination with a pair of keepers, a pair of strips adapted at their ends to engage said keepers, means to connect the strips to permit expansion and contraction thereof, and means borne by the strips to lock the strips against contraction operable by lateral movement of the strips. 70

4. In a loose leaf binder, a pair of flexible strips, a pair of keepers, said strips being 80 adapted at their ends to engage said keepers, means to connect the strips to permit expansion and contraction thereof, and means to lock the strips against contraction operable by flexure of the strips. 85

5. In a loose leaf binder, a pair of flexible strips, a pair of keepers, said strips being adapted at their ends to engage said keepers, means to connect the strips to permit expansion and contraction thereof, and means 90 to lock the strips against contraction operable by flexure of the strips, said strips being thin so as to be insertible between the leaves of a book and the book acting to prevent accidental flexure of the strips. 95

6. In a loose leaf binder, in combination with a pair of keepers, a pair of strips adapted at their ends to engage said keepers, means to connect the strips to permit expansion and contraction thereof, and means rigidly borne by one of the strips and receivable in a socket provided therefor in the other strip to lock the strips against contraction. 100

In testimony whereof I affix my signature 105 in presence of two witnesses.

JOSEPH M. TOWNE.
